United States Patent Office.

JOHN VAUGHN, OF MIAMI COUNTY, AND ELI CHAMNESS, OF GRANT COUNTY, INDIANA.

Letters Patent No. 78,031, dated May 19, 1868.

IMPROVEMENT IN SUBSOIL-PLoughs.

The Schedule referred to in these Letters Patent and making part of the same.

TO ALL WHOM IT MAY CONCERN:

Be it known that we, JOHN VAUGHN, of Miami county, and ELI CHAMNESS, of Grant county, in the State of Indiana, have invented a new and useful Improvement in Subsoil-Ploughs; and we do hereby declare that the following is a full, clear, and exact description of the construction and operation of the same, reference being had to the accompanying drawings, making a part of this specification, in which—

Figure 1 is a side elevation.

Figure 2 is a front view.

Like letters in both figures of the drawings indicate like parts.

Our improvement relates to that class of excavating-machines used for ploughing up the ground, with a series of spades acting as adjuncts of the plough for a better accomplishment of the same.

Its nature consists in the combination of a number of spades with a plough and jack, together with framework for supporting and drawing it, whereby an extremely simple and efficient article is obtained for the intended purpose.

To enable any one skilled in the art to make and use our invention, we will proceed to describe its construction and operation.

A represents a framework, from which project two angular A-shaped pieces on either side, which are united at their apex, *a*, and with handles *b* in the rear for directing and adjusting the machine in position. This frame rests upon an axle, *c*, of the spade-wheel, and has a dash-board, *d*, on one side thereof, which inclines at a suitable angle towards and under the rim of the spade-wheel, which dash-board is to prevent the earth from falling back into the furrows.

B is the wheel, whose axle rests upon the body or frame. It is three feet in diameter on the widest side, sloping inwardly at an angle of forty-five degrees, and about nine inches wide. Attached to the wheel, at the rim *e*, and projecting outwardly, is a series of spades, *h*, which spades are ten inches long from point to point, and about nine inches wide. The spades are attached to the rim of the wheel *e*, and to the flange *f* thereof, which strengthens and sustains them in position.

C represents a jack or cleaner, whose axle is at *g*, and rests upon the frame or body A, and whose spades are revolved by the motion of those of the wheel B while cleaning the earth therefrom.

The operation is as follows: The earth, upon being ploughed up by the machine, is immediately thereafter spaded, and fully broken up and thrown again upon ploughed ground, but should any earth cling to the spades, it is cleaned off by the jack, which greatly facilitates the work. It can be used with or without an ordinary plough.

To the frame is attached the plough D, which may be of any style for the work to be performed.

The frame will be made of timber, two and a half by four inches, and three feet wide.

Having thus fully described our invention, what we claim therein as new, and desire to secure by Letters Patent, is—

1. The construction and arrangement of the wheel B, substantially in the manner and for the purpose as herein set forth.
2. The combination of the frame A and dash-board *d* with the wheel B, substantially in the manner and for the purpose as herein set forth.
3. The combination of the plough D with the wheel B, substantially in the manner and for the purpose as herein set forth.
4. The combination of the jack or cleaner C and frame A with the wheel B, substantially in the manner and for the purpose as herein set forth.

JOHN VAUGHN,
ELI CHAMNESS.
